(57) **CLAIM**

The ornamental design for a wire rod shelf bracket, as shown and described.

DESCRIPTION

FIG. 1 is a top front perspective view of a wire rod shelf bracket showing our new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a front perspective view thereof showing the environment in broken lines.

The broken lines FIG. 8 show the environment of the wire rod shelf bracket and form no part of the claimed design.
